(57) CLAIM

The ornamental design for a knife sharpener, as shown and described.

DESCRIPTION

FIG. 1 is a perspective view of a knife sharpener showing my new design from above;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a rear view thereof;

FIG. 8 is an additional perspective view thereof from below; and,

FIG. 9 is a right side view of the knife sharpener, shown removably attached to a knife handle in broken line for completeness of illustration.

The broken lines shown in the drawings are for illustrative purposes only and form no part of the claimed design.
